Primary Examiner — Sharon S Oum(74) *Attorney, Agent, or Firm* — McGarry Bair PC(57) **CLAIM**

The ornamental design for a ceiling fan light cage, as shown and described.

DESCRIPTION

FIG. 1 is a bottom perspective view of a light cage in the environment of a ceiling fan, showing my new design; FIG. 2 is a top perspective view of the light cage of FIG. 1; FIG. 3 is a top view of the light cage of FIG. 1; FIG. 4 is a bottom view of the light cage of FIG. 1; and, FIG. 5 is a side view of the light cage of FIG. 1. The dash-dash broken lines illustrate portions of the ceiling fan light cage and the ceiling fan environment. The dash-dot broken lines illustrate boundary lines. None of the broken lines form part of the claimed design.
